UNITED STATES PATENT OFFICE.

HENRY C. SIEMS AND HEINRICH DEWITZ, OF WHEATLEY, ARKANSAS.

EXTENSION-LADDER.

No. 874,801.

Specification of Letters Patent.

Patented Dec. 24, 1907.

Application filed June 28, 1907. Serial No. 381,265.

To all whom it may concern:

Be it known that we, HENRY C. SIEMS and HEINRICH DEWITZ, citizens of the United States, residing at Wheatley, in the county 5 of St. Francis and State of Arkansas, have invented certain new and useful Improvements in Extension-Ladders, of which the following is a specification.

The present invention has for its primary 10 object to provide an improved ladder which is peculiarly designed so as to be readily collapsed when not in use.

The invention further contemplates the provision of supporting members for the ladder which serve to hold the ladder in an upright position when extended and also form a truck to facilitate transportation of the ladder when folded.

A still further object is to design a simple 20 and efficient ladder of this character which can be utilized either as a step ladder or as an extension ladder according to circumstances.

For a full description of the invention and 25 the merits thereof and also to acquire a knowledge of the details of construction and the means for effecting the result, reference is to be had to the following description and accompanying drawings, in which:

30 Figure 1 is a perspective view of a ladder embodying the invention, the same being shown as extended. Fig. 2 is a similar view showing the ladder when folded. Fig. 3 is a perspective view showing the device when 35 used as a step ladder. Fig. 4 is a detail view of one of the foot boards. Fig. 5 is an enlarged detail of one of the clamps by which the extensions are connected to the legs. Fig. 6 is a view of a portion of one of the 40 sides of the ladder, showing a modification.

Corresponding and like parts are referred to in the following description and indicated in all the views of the drawings by the same reference characters.

45 In general the invention comprises a ladder in which the side pieces have a lazy tong construction and can be extended or collapsed as desired. Each of the sides of the ladder comprises a plurality of bars 1 which 50 are pivotally connected at their ends as indi-

cated at 2 and at their intermediate points upon the rods 3 constituting the foot-pieces or rungs of the ladder. Supporting bars 4 are pivotally connected to one set of the bars 2 at the lower end of the ladder, the end portions of the bars being curved upwardly and connected by the rod 5. It will also be observed that a foot-piece or cross bar 6 joins intermediate portions of the supporting bars 4. Pivots connected to the extremities of 55 the opposite set of the bars 1 at the lower end of the ladder are the levers 7. These levers are also pivoted to the supporting bars 4 at 8 and are extended beyond the latter, the extremities of the levers being formed with the 60 prongs 9 designed to engage the ground or other surface upon which the ladder rests in order to prevent slipping. Plates 10 are applied to these projecting ends of the levers 7 and a shaft 11 is journaled between the said 65 plates, wheels 12 being mounted upon the shaft. When the handle portions of the levers 7 are swung upwardly and the foot-piece 6 pressed downwardly the sides of the 70 ladder are extended as shown in Fig. 1. 75

Each side of the ladder is provided with a transverse tie member 13 connecting corresponding ends of the bars 1, and a longitudinal tie member 14 connecting intermediate portions of the bars 1, each of said tie members having one end adjustably secured to 80 the ladder whereby the lazy tong construction can be extended to any required degree and then rigidly locked in position. In the present instance these tie members 13 and 14 are in the nature of chains, a selected one of the links being designed to engage a suitable projection upon the ladder. A shaft 15 connects the extremities of one pair of the bars 1 at the upper end of the ladder and carries the rollers 16 which are designed to engage a wall or other vertical surface when the ladder is being extended against the same. When the ladder is folded as indicated in Fig. 2 the bars 1 of the lazy tong construction are collapsed against the levers 7 and the wheels 12 are lowered into engagement with the ground or other surface while the supporting bars 4 are swung outwardly so as 85 to form suitable supports for the truck. 90 95 100

When in this position the ladder can be readily wheeled from place to place by grasping the handle portions of the levers 7 and lifting the curved ends of the supporting bars 4 away from the ground. It is also contemplated under certain conditions to utilize the device as a step ladder, and for this purpose the legs 17 are provided, the said legs being suitably connected by the diagonal brace members 18 and the transverse braces 19. Each of the legs 17 has an extension 20 and the said extensions are adjustably connected to their respective legs by the clamping members 21 which are in the nature of loops 15 and have their inner faces roughened to prevent longitudinal slipping of the extensions after being properly adjusted. The lower portions of the extensions 20 are connected by a chain 22 and tie rods 23 are loosely connected at one end to the legs 17, the opposite extremity of each tie member being forked at 24 for engagement with one of the rungs 3 of the ladder, the two arms of the fork being designed to be connected by a pin 25 as shown upon the drawings. The upper extremities of the legs 17 carry the spaced extensions 25 designed to receive the bars 1 at the top of the ladder, the said extensions being connected by pins 26 extending 30 through the said bars. It will thus be seen that these legs 17 are detachably connected to the ladder and are extensible so as to be adjusted to conform to the degree to which the lazy tong construction is extended.

35 When the device is utilized as a step ladder it is designed to employ the foot boards 27 which are shown as formed in two hinged sections and provided at their extremities with the projections 28 designed to be received within corresponding openings 29 in the bars 1 of the lazy tong construction. By forcing the hinged central portion of the foot-pieces 27 upwardly so that the two sections of the board are disposed at an angle to 40 each other, the projections 28 can be either disengaged from or thrown into engagement with the openings 29, the foot boards 27 being locked in position when the hinged central portions are pressed downwardly so that 45 the two sections of the board are in alignment with each other.

50 From the foregoing description it will be readily apparent that the ladder can be readily transported from place to place owing to the truck formation produced by the levers 7 and supporting bars 4 when the ladder is folded. Furthermore the ladder is so constructed as to be quickly extended by a single man for the purpose of scaling a wall or 55 crossing a stream or spanning the distance between two supports. When employed for this latter purpose it may be found desirable

in the construction of the larger sizes of the ladders to provide the lazy tong construction of the sides with the lateral extensions 60 30 which serve to increase the strength of the device when used as a beam.

Having thus described the invention, what is claimed as new is:

1. In a ladder, the combination of collapsible side pieces, foot pieces connecting the side pieces, and coöperating levers and supporting bars pivotally connected to the side pieces of the ladder and to each other, one of said members carrying wheels and the said members coöperating to form a truck for the ladder when collapsed. 70

2. In a ladder, the combination of collapsible sides, foot pieces connecting the side pieces, coöperating levers and supporting bars pivotally connected to the side pieces of the ladder and to each other for controlling the collapsing of the side pieces, and means carried by the levers for coöperation with the same and the supporting bars 80 75 to form a truck for the ladder when collapsed.

3. In a ladder, the combination of side pieces having a lazy tong construction, foot-pieces connecting the side pieces, a lever pivoted to one end of the ladder, a wheel carried by the lever, and a supporting bar also pivoted to the ladder and coöperating with the lever to form a support for the ladder when extended and a truck for the ladder when folded. 90

4. In a ladder, the combination of side pieces having a lazy tong construction, foot-pieces connecting the side pieces, a lever applied to one end of the ladder, a supporting 100 bar applied to one end of the ladder, and a wheel carried by the lever, the lever and supporting bar forming a truck for the ladder when folded.

5. In a ladder, the combination of side 105 pieces having a lazy tong construction, foot pieces connecting the side pieces, levers pivotally connected to the side pieces of the ladder, wheels carried by the levers, and supporting bars pivotally connected to the side 110 pieces of the ladder and to the levers, the free ends of the supporting bars being curved outwardly and connected by a rod upon which the foot is placed when extending the ladder, the said levers and supporting bars 115 coöperating to form a truck for the ladder when collapsed.

6. In a ladder, the combination of side pieces having a lazy tong construction, foot pieces connecting the side pieces, supporting 120 bars pivotally connected to the side pieces of the ladder, levers pivotally connected to the side pieces of the ladder and to the supporting bars, the said levers being provided with

prongs for engaging the surface upon which the ladder rests to prevent slipping, and wheels mounted upon the levers, the said levers and supporting bars coöperating to

5 form a truck for the ladder when collapsed.

7. In a ladder, the combination of side pieces comprising a plurality of pivoted bars forming a lazy tong construction, said bars being provided with sockets, and removable

10 foot boards comprising hinged sections car-

rying projections adapted to enter the before mentioned sockets.

In testimony whereof we affix our signature in presence of two witnesses.
